UNITED STATES PATENT OFFICE.

ARTHUR RUSSELL, OF HUCKNALL, ENGLAND.

COAL-CUTTING MACHINE.

1,414,586.

Specification of Letters Patent. Patented May 2, 1922.

Application filed April 16, 1920. Serial No. 374,357.

To all whom it may concern:

Be it known that I, ARTHUR RUSSELL, a subject of the King of Great Britain, residing at Hucknall, in the county of Nottingham, England, have invented a new and useful Coal-Cutting Machine, of which the following is a specification.

This invention relates to improvements in and applicable to coal cutting machines and 10 has reference to the chain and disc type of machine.

The present invention has for its object the provision of improved means for carrying the cutting tools, means for preventing 15 the slack or dirt from being carried back into the machine after the tools have left the cutting face, and improvements in the means for and in the method of cutting coal. A further object of the present invention is 20 the combination of the improved tool carrier with apparatus for removing the slack or dirt from the vicinity of the machine, wherein the improved carrier may be adapted to actuate said apparatus without re- 25 source to an independent source of power.

According to this invention the tools are carried by carriers pivotally mounted upon the tool boxes and such carriers are adapted to be rotated after leaving the cutting face 30 for the purpose of preventing the slack and dirt being carried back into the machine. Scrapers are also provided, preferably constituting the front face of each carrier and such scrapers further assist in carrying 35 away the slack or dirt from the cutting face. The improved cutters are also preferably used in conjunction with the apparatus for removing the slack or dirt as described in the specification of British patent applica- 40 tion No. 28216 of 1919.

For the purpose of more fully describing this invention reference will now be made to the accompanying drawings wherein:

Fig. 1 is a part sectional view of one form 45 of the improved cutter,

Fig. 2 is a plan part sectional on A—B Fig. 1,

Fig. 3 is an end elevation of Fig. 1 part sectional through C—D,

50 Fig. 4 is a diagrammatic view showing different positions of the tools,

Fig. 5 is an elevation part sectional through the centre line of one tool showing

the cutter in the backward or non-cutting position,

Fig. 6 is a plan of Fig. 5 part sectional through E—F,

Fig. 7 shows the application of the improved cutter to apparatus for clearing away the slack or dirt from the immediate vicinity of the machine,

Fig. 8 shows the application of this invention to a disc type of machine and the combination therewith of apparatus for clearing away the slack or dirt from the immediate vicinity of the machine, and

Fig. 9 is a sectional view through G—H Fig. 8.

In the drawings herewith Figs. 1, 2, 3, 5, 6 and 7 show the application of this invention to a chain machine wherein tool boxes 1 connected by links 2 carry pivoted carriers 3. Conveniently this invention may be applied to any form of chain or disc machine and in the modification shown in Figs. 8 and 9 wherein is shown the adaption of this invention to a disc machine, the tool boxes 1 and links 2 are dispensed with, but the carriers 3 are as illustrated and described with reference to Figs. 1 to 7, excepting that the flanges *b* may be curved as and for the purposes hereinafter described. In the arrangement shown in Figs. 1 to 7 bosses 4 carried by the links 2 are adapted to be received at both extremities of the boxes 1 and the boxes and links held in position by bolts or the like passing through holes 5 centrally situated within said bosses. Shoulders 6 are also preferably provided on the boxes and links and are adapted to bear against a corresponding shoulder provided along the inner face of the gib 7 (Fig. 3),

The carrier 3 is preferably made in one piece and comprises a central portion *a*, side members or flanges *b* provided with bosses as at *c* adapted to bear on the upper recessed portion *d* of the box 1, a shoulder being provided as at *e* between said portion *d* and the main portion of the box and a slight clearance being preferably allowed between the lower face of the boss *c* and the flange *e*.

The carrier 3 is pivotally mounted upon a bolt 8 passing through such carrier and the upper portion *d* of the box 1, and when in the cutting position as shown in Figs. 1, 2 and 3 the carrier 3 is held from rotation

by reason of the flanges *b* bearing on the upper face of the gib 7. A flange may be provided as at *f* for limiting the rotation of the carrier 3, but if it is required to reverse the chain, such flange may be dispensed with, the upper portion *d* of the box 1 then being symmetrical about the vertical centre line of the bolt 8.

After leaving the cutting face and when 10 the links and boxes are engaged by the sprocket wheel, each carrier 3 is adapted to be rotated through 90 degrees into the backward or non-cutting position, Figs. 5 and 6, the lower portion of the underneath face of 15 the central portion *a* formerly tangential to the upper curved face of the upper portion *d* of the box 1 then bearing on the rear vertical face of said box and thus holding the carrier from further rotation.

20 The tools 9 may be of any convenient design and shape and there may be one or more than one tool carried by each box. Different arrangements of the tools are represented in Fig. 4 wherein are shown 25 straight tools *g* vertical when in the cutting position as shown in Fig. 1 and outwardly projecting tools *h*. If such latter tools are used the carrier 3 is preferably widened as shown, and in a further modification a bent 30 tool *k* is employed, the pick of such tool being central. Any other convenient form of tool may, however, be employed and any combination of the different tools may be used on each box.

35 Such tools 9 may extend through the flanges *b* of the carrier 3 to bear on the circumference of the bolt 8 or in the modification shown in Fig. 4 the tools 9 are slotted as at *p* or a hole is provided in said tools for 40 accommodating the bolt 8.

For the purpose of maintaining such tools when extending only to the bolt 8, in their placed positions, a bolt 10 may be adapted to pass through said tools and the carrier 3, 45 such bolt being held in position in any convenient manner. In a modification a set screw is provided as at 11 this means of positioning the tools allowing of same being moved further in or out of the carrier for 50 the purpose of alignment.

Conveniently situated on the front of some or all of the boxes is a scraper 12, preferably rectangular and extending above and beyond the carrier 3 to which said scraper is 55 attached by set screws or the like 13. Conveniently slots 14 are provided on the faces of the scrapers for the purpose of laterally adjusting same and the function of said scrapers is to carry the slack and dirt deposited during the cutting of the coal to the 60 end of the machine.

For the purpose of traversing the chain, sprocket wheels 14^a are adapted to engage same at both ends of the machine and when 65 engaged by said wheels the boxes 1 and the

links 2 do not bear on the gib 7. As shown in Fig. 7 the gib does not extend to the end of the machine and thus the carriers 3 carried by the boxes 1 engaging with the sprocket wheel are free to rotate about the pivot 8, the flanges *b* no longer being held from rotation by reason of bearing on the upper edge of the gib.

If it is required to reverse the direction of traverse of the chain it is only necessary 75 according to this invention to remove the tools from the carriers and insert same in the opposite direction with their picks pointing in the direction of traverse provided there is no flange as at *f* on the box 1 and 80 provided an adjustable gib member is provided as at 7^a Fig. 7.

If the chain is traversed in a direction opposite to that depicted in Fig. 7 it is essential that the flanges *b* of the carriers 3 85 should be riding on the edge of the member 7^a immediately before the picks of the tools come into contact with the coal. Said member 7^a (indicated dotted) is thus adapted to be moved outwardly to allow of the flanges 90 *b* riding along the outer edge thereof, and upon once more reversing the direction of traverse of the carriers said member is moved back to its position as shown to allow 95 of the carriers rotating when bearing against the stop.

After leaving the cutting face 8^a each carrier in succession is adapted to bear against a conveniently situated stop or the like 15 which rotates the carrier through 90 degrees 100 as shown in Figs. 5 and 6. The slack carried forward by each scraper 12 is thus left by each box as the carrier 3 is rotated and any convenient means may be employed for removing such slack from the vicinity of the 105 machine. In the arrangement shown in Fig. 7 scraping members 16 carried by chains 17 are adapted to travel forward as each box comes into position and such members thus carry forward the slack deposited by each 110 scraper 12 thus allowing of said slack being more readily handled and reducing risk of danger to the operator by his too nearly approaching the machine as is at present necessitated.

In the arrangement shown a sprung rod 115 18 is adapted to be reciprocated by each box in succession to rotate a claw arm 19 engaging a toothed wheel 20, such wheel being coaxial with the sprocket wheels adapted to 120 traverse the chains 17.

The boxes may be adapted to rotate a slotted member 21 pivoted at 22 for the purpose of reciprocating the rod 18, said rod carrying a pin 23 fitting into the slot 24. For 125 increasing the throw of the arm 19, pins 22 and 25 carried by the member 21 may be adapted to slide within grooved slots 26 carried by suitably situated members, said 130 grooves being such that when the pins 22

and 25 are at the end of their travel the respective box ceases to bear on the member 21; the lateral motion of such latter member being possible by reason of the slot 24 provided therein.

The various members are carried to their normal positions under the action of the sprung rod 18, when they are adapted to be actuated by the next box in succession to 10 traverse the scraping members 16.

After, or immediately before, each box leaves the sprocket wheel 14^a and returns along the gib to the cutting face, the flanges b of the carriers 3 are adapted to bear 15 against a projecting face m, preferably inclined, to rotate such carriers to their normal positions, the flanges b then riding on the edge of the gib removed from the cutting face 8^a. At the further extremity of the 20 machine the gib may enclose the sprocket wheel so that the flanges b are bearing on such gib immediately before commencing cutting, and cease to bear on such gib immediately after leaving the cutting face as 25 shown in Fig. 7.

In the application of this invention to a disc machine as shown in Figs. 8 and 9 the disc 27 is provided at intervals with projections 28. The carriers 3 carrying the 30 tools 9 are of the same construction as herein before described and are pivotally carried by the bolts 8 passing through the projections 28. The flanges b of the carriers 3 bear the outer edge bracket plate 29 enclosing the disc 35 27, such flanges being curved so that they sit flush with the outer edge of said bracket plate or plates.

The disc 27 is rotated by a toothed pinion 30 engaging teeth 31 provided around the 40 upper face of said disc and said pinion is mounted upon a shaft 32 carried by brackets 33 and driven from any convenient source of power.

The carriers 3 after leaving the cutting 45 face 34 are adapted to bear against a conveniently situated stop or the like 35 and upon bearing against such stop the carriers are rotated through 90 degrees, thus depositing the slack or dirt carried from the cutting face by the scrapers 12 and preventing said slack or dirt from being carried back into the machine.

For allowing of the rotation of the carriers 3 the bracket plates 29 are cut away as at 50 36. Conveniently a cut away portion 36 is provided at both sides of the pinion 30, said portion 36 on the side of the pinion nearer the cutting face being enclosed by a removable bracket plate 37 along the edge of which 60 bear the flanges b of the carriers 3.

By reason of providing two cut away portions 36 and a removable bracket plate 37 reversing of the disc is facilitated, the bracket plate 37 being removed from its 65 former position to disclose the open cut

away portion 36. The carriers 3 will then be rotated after leaving the cutting face, but before leaving such face will bear on the edge of the plate 37 in its new position. Conveniently holes 38 may be provided in 70 the plates 29 and 37 and such latter plates affixed to the former by nuts and bolts or the like as at 39.

For the purpose of removing the slack or dirt deposited by the scrapers 12 from the 75 vicinity of the machine, independent scrapers 40 may be used in combination with this invention. As shown in Figs. 8 and 9 the scrapers 40 carried by chains 41 are driven by a chain 42 actuated by a sprocket wheel 80 43 coaxial with the shaft 32, and the line of traverse of said scrapers is at right angles to the cutting face 34.

The disc machine as above described may be of any convenient design and actuated in 85 any convenient manner and may be cut away as at 44 for the purpose of lightening same.

By reason of applying this invention as herein described the slack or dirt is prevented from being carried back into the machine 90 after the tool boxes have left the cutting face and if the rotatable carriers are used in conjunction with the scraping members 16 risk of danger to the operator is considerably reduced.

I claim:—

1. In coal cutting machines rotatable tool carriers adapted to bear against stops after leaving the cutting face, said stops rotating the carriers, said carriers depositing the 100 slack or dirt carried from the cutting face upon rotating, stops adapted to bear on the carriers to rotate same into the cutting position after depositing the slack or dirt, and means for holding the tools carried by the 105 carriers up to the coal when traversing the cutting face.

2. In coal cutting machines the tools positioned by carriers rotatably mounted upon pivots, a bracket plate, flanges on the carriers riding along the edge of the bracket plate, said flanges holding the tools up to the coal, the carriers adapted to bear against stops after leaving the cutting face, the bracket plate being cut away opposite said 110 stops to allow of the carriers rotating when bearing thereon, the slack or dirt carried from the cutting face by scrapers to the front of said carriers being deposited upon rotation thereof, and stops to rotate the carriers into the cutting position after depositing the slack or dirt.

3. A coal cutting machine provided with tools adjustably positioned within carriers, set screws for holding said tools in position, 115 tool boxes, the carriers rotatably mounted upon pivots carried by the tool boxes, a bracket plate, flanges on the carriers riding on the edge of the bracket plate, bosses on the carriers sitting flush within recesses on 120 125 130

the boxes, stops to bear on said carriers to rotate same after leaving the cutting face, the bracket plate being cut away to allow of said rotation, means for limiting same, 5 scrapers to the front of the carriers and stops for again rotating the carriers into the cutting position before reaching the cutting face.

4. In coal cutting machines the tool carriers rotatably mounted upon pivots carried by the boxes, recesses on said boxes to accommodate bosses on the carriers, backwardly extending flanges on the carriers riding on the edge of the bracket plate, said 10 bracket plate cut away to allow of rotation of said carriers, stops to rotate same after leaving the cutting face, scrapers to the front of said carriers to carry away the slack from the cutting face, said slack deposited 15 upon rotation of the carriers, stops for rotating same into the cutting position after depositing said slack and means for removing same from the vicinity of the machine.

5. The combination with a coal cutting

machine provided with rotatable carriers 25 adapted to remove the slack or dirt from the cutting face, of scraping members for removing the slack deposited by the carriers from the vicinity of the machine, chains for supporting said scraping members, means 30 for rotating said carriers and said carriers adapted to cause said chains to move after they have been rotated substantially as and in the manner specified.

6. The combination with a coal cutting 35 machine provided with rotatable tool carriers adapted to be rotated after leaving the cutting face to deposit the slack or dirt carried therefrom, of scraping members arranged at right angles to said tool carriers 40 and adapted to carry away the deposited slack or dirt from the vicinity of the machine and said tool carriers adapted to actuate said scraping members substantially as and for the purpose specified. 45

In witness whereof I have hereunto set my hand.

ARTHUR RUSSELL.
